John Helm,

By

Almae O. D. S.

Attorney

UNITED STATES PATENT OFFICE.

JOHN HELM, OF MEADE, KANSAS.

SADDLE RING.

Application filed May 19, 1925. Serial No. 31,332.

To all whom it may concern:

Be it known that I, JOHN HELM, a citizen of the United States, residing at the city of Meade, in the county of Meade and State of 5 Kansas, have invented certain new and useful Improvements in a Saddle Ring, of which the following is a specification.

This invention relates to an improved saddle ring which has been designed to take 10 the place of a three-quarter ring now commonly used upon marketed horse saddles.

More precisely, the invention has reference to an improved ring which is to be used in connection with saddle rigging, one feature of the ring being the strength that it embodies to withstand strenuous pulls, and stresses exerted thereon when in position on 15 the animal.

Another feature is the ornamental configuration brought about by an arrangement of parts also serving to render the ring extremely sturdy, and such as to be used successfully with well dressed saddle trees, the same preventing bulging of straps and mis- 20 placement of the same.

Other features and advantages of the improved ring will be made apparent from the following description and the accompanying drawing, in which:

30 Figure 1 is a side elevation of a horse saddle tree and rigging thereon, showing straps of the rigging connected with the improved ring.

Figure 2 is an enlarged faced view of the 35 improved ring.

Figure 3 is a central vertical section taken approximately upon the plane of the line 3—3 of Figure 2.

Referring to the drawings, and confining 40 attention more particularly to Figure 1 it will be observed that the reference character 1 designates a conventional type of saddle tree including the usual cantle 2, and pommel 3. The reference character 4 designates 45 a rear rigging strap adapted to be fastened at its forward end to the improved ring. I also show a common tie strap 5 adapted to be associated with the ring, a girth 6 to which the tie strap is connected, and the cus- 50 tomary additional fore strap 7 employed in association with the pommel or horn 3. So far as I am aware, the ordinary ring em- 55 ployed in place of the one shown in Figure 1

is of a substantial three-quarter type, and from experience it has been observed that owing to the peculiar arrangement of the various straps, the strains and stresses are unevenly distributed, resulting in distortion of the saddle tree covering, rigging straps, etc. I therefore propose a novel ring which 60 is such as to accommodate the various straps shown and will operate to advantage in distributing strains in a uniform and practical manner. The ring may be designated generally by the reference character 8 and by 65 directing attention more particularly to Figure 2 it will be seen that the improved ring comprises an annulus 9 provided with a central cross plate 10. At the bottom is an arcuate and relatively small slot 11 and on 70 the left hand side is a segmental member 12 defining a relatively large segmental opening 13. From Figure 3 it will be observed that the cross plate 10 is flat on its inner face while the outer face has its marginal edges beveled as at 14 to render it 75 ornate. It will also be noted that the plate is comparatively wide and that it is joined with the annulus 9 in a manner to decidedly reinforce the latter. Thus, the improved 80 ring is made very sturdy. Owing to the configuration of the reinforcing plate, rings must be made both "left" and "right," thus allowing the flat sides of the plate to bear 85 against the body of the animal, and to prevent ring sores from forming.

As shown in Figure 1, when the ring is in place upon the rigging, the pommel strap 7 is passed through the upper portion, and the rigging strap 4 is attached to the segmental 90 member 12 through the opening 13. The small slot 11 serves to accommodate the tie strap 5, the same being stitched in place as indicated, and passed through the ring again and upwardly and anchored in the manner 95 shown.

The improved ring is primarily intended for use in connection with the front girth particularly, but can be used to advantage with double rigged saddles. The annulus 100 of the ring should not be cylindrical in cross section, but should be beveled or of the cross section plainly shown in Figure 3. With this configuration, ring sores will be overcome and bulging out of the skirt and 105 other covering for the saddle will be pre-

vented. Further, holes will not be rubbed through the skirt leather with a ring of this type. These and other advantages and features of the improved ring have doubtless 5 been made apparent by the foregoing description in connection with the accompanying drawing. For this reason it is believed that a clear understanding of the invention is now at hand, and a more lengthy description is therefore unnecessary.

While the preferred embodiment of the invention has been shown and described, it is to be understood that minor changes coming within the field of invention claimed 15 may be resorted to if desired.

Having thus described the invention, what I claim as new and desire to secure by Letters Patent is:—

A saddle rigging ring of the class described comprising a concentric annulus provided with a central integral cross plate flat upon its inner face, said annulus being provided at its bottom with an arcuate slot, and a segmental member integral with one side of the annulus and spaced therefrom to provide a segmental opening for passage of a predetermined saddle strap. 20 25

In testimony whereof I affix my signature.

JOHN HELM.
